SHOE SUPPORT

Earl A. Bessom, Marblehead, Mass., assignor to
 United Shoe Machinery Corporation, Paterson,
 N. J., a corporation of New Jersey

Application November 3, 1932, Serial No. 640,961

20 Claims. (Cl. 12—31.5)

This invention relates to the manufacture of shoes and is illustrated as embodied in a heel-seat-fitting machine having a support comprising an expansible form for positioning in the machine the heel ends of shoes off the last and for clamping the shoes against movement after they have been positioned in the machine.

In United States Letters Patent No. 1,902,824, granted March 28, 1933 on an application filed in my name there is disclosed a heel-seat-fitting machine in which right and left shoes upon lasts may be effectively centered and clamped against movement in the machine by mechanism including arms which respectively engage the opposite sides of the counter portion of the outside of the shoe with a substantial amount of pressure. In order further to insure that the shoe is held securely in the above machine during the heel-seat-fitting operation the overlasted counter portion of the shoe on the last is forced by such mechanism against rand crease entering plates of the machine.

It is an object of the present invention to provide an improved machine which will operate upon shoes off the last to fit their heel seats for the reception of wood heels. With this in view I have provided a form well adapted for use in the machine of the above-identified application, which will effectively support the marginal parts of the heel seat of the inside of the shoe as the overlasted counter portion of the shoe is forced against the crease plates and which will also support the sides of the counter portion of the shoe against distortion under pressure of the centralizing and clamping arms. In order to expedite the heel-seat-fitting of shoes off the last, the form should be, and as illustrated is, of such shape that the operator can readily mount the shoe upon the form and remove the same therefrom at the beginning and the end respectively, of such operation. Furthermore, the illustrated form automatically co-operates with other parts of the machine to position and to clamp the shoe in the machine without the operator having to perform any operations not required when fitting the heel seats of shoes on the last.

While the illustrated expansible form is described with reference to the above-mentioned machine, it will be understood that such form may be used for supporting and positioning shoes off the last in various other types of machines.

It is a further object of the present invention to provide, in a machine for operating upon the heel ends of shoes, an expansible form which will automatically and effectively support and

centralize a shoe off the last as the shoe is clamped in a heel-seat-fitting or other machine.

With the above objects in view and in accordance with a feature of the present invention, the illustrated machine is provided with an expansible support or form shaped for reception within the heel end of a shoe and with mechanism to force the support toward a plate which is shaped and arranged to engage the rand crease of the shoe, the support being constructed for expansion to force the same into engagement with the counter portion of the inside of the shoe as the shoe is forced against the plate by such mechanism. Preferably such engagement occurs over a relatively large area to insure a firm support for the shoe in the machine.

The illustrated expansible support comprises a pair of forms which are pivotally mounted for movement toward and away from each other upon a plunger. The plunger is yieldingly supported upon a block that may be readily mounted in operative position upon a jack post of the above-mentioned machine in place of a last pin block, when it is desirable to change from on-the-last to off-the-last work. The block is provided at its upper end with a pair of wedge faces against which the respective forms are held by a spring carried by the forms. When a shoe mounted upon the forms and having its overlasted counter portion in engagement with rand crease entering plates of the machine is positioned in the machine, the jack post is raised to force the shoe against the plates. Upward movement of the jack post causes the wedge faces to force the forms into engagement with the counter portion of the inside of the shoe, prior to exerting a clamping pressure against the outside counter portion of the shoe by centralizing and clamping arms, and thereby preventing the counter portion from being distorted by such arms. As the jack post is raised the top faces of the forms, which engage a substantial portion of the heel seat of the inside of the shoe, effectively support the heel seat and cooperate with the crease plates to clamp the shoe in the machine.

In the drawings, Fig. 1 shows a longitudinal vertical section of a portion of the heel-seat-fitting machine disclosed in the above-mentioned United States Letters Patent No. 1,902,824 and also shows in side elevation the illustrated expansible form and mechanism for operating the same incorporated in such machine;

Fig. 2 is a plan view of the portion of the machine illustrated in Fig. 1;

Fig. 3 is a sectional view of the machine taken along line III—III of Fig. 2; and

Fig. 4 is an exploded view illustrating in perspective the expandable form and parts used in 5 mounting the same upon the jack post of the machine illustrated in Figs. 1 and 2.

An illustrated expandable form 20 is described with reference to its use in the heel-seat-fitting machine disclosed in United States Letters Patent No. 1,902,824. In order to equip such machine so that it may be effectively used for fitting the heel seats of shoes off the last for the reception of heels, a jack post 22 of the illustrated machine is provided with a block 24 (best shown 10 in Figs. 1 and 3) constructed and arranged to replace a last pin block (not shown) which is positioned upon the jack post 22 when the machine is operating upon shoes on the last.

The block 24 is constructed to receive a head 20 25 (Fig. 1) comprising the expandable form 20 which consists of a pair of pivotally adjustable angular forms 20a, 20b, shaped and arranged to engage the heel and the counter portions 26 and 28 of the insides of shoes of different sizes 25 and styles.

The jack post 22, if desirable, may be formed integrally with the block 24 and is bored to receive a cylindrical rod 30 (Fig. 1) which supports the jack post through a spring 32, the upper end 30 of which engages a shoulder 34 of the post and the lower end of which is included in an axially extending recess 36 formed in the cylindrical rod 30. In order to swing the jack post 22 from loading or forward position shown in dotted lines 35 in Fig. 1, to an upright position to cause a shoe mounted thereon to engage with a back gage 38, thereby positioning the shoe lengthwise in the machine, the rod 30 is pivotally mounted upon a pin 40 of the main frame of the machine. As 40 the operator swings the jack post 22 rearwardly of the machine he grasps the shoe and depresses the same slightly against the pressure of the spring 32 so as to bring the rand crease of the shoe into engagement with a pair of crease plates 42 45 which form a V-shaped opening 43 and are mounted for pivotal movement in the machine frame about a vertical axis passing through point 44 (Fig. 2). The spring 32 is of sufficient strength to force the shoe with a slight amount of pressure against the underside of crease plates 42 when the operator releases his grasp of the shoe.

While the shoe upon the jack post 22 is being swung rearwardly it is centered in the machine by the combined operation of a V-shaped gage 46 55 (Fig. 2), which is mounted for rectilinear movement in a slide 48, and a pair of angular arms 50 comprising a plurality of parts and pivotally mounted for equal and opposite movement upon the slide 48. The V-shaped gage 46 is normally 60 held in a forward position with respect to the slide 48 by a spring 52 and when moved rearwardly against the spring 52 swings the arms 50, toward each other until they lightly engage the counter portion of the outside of the shoe in the 65 vicinity of its breast line. Such movement is effected by providing the V-shaped gage 46 with a pin 54 which is movable along a slot 56 formed in one of the arms 50. When the arms 50 are in engagement with the shoe, the V-shaped gage 70 46, together with the arms 50 are moved rearwardly upon the slide 48 until the rear end of the counter portion of the shoe engages the back gage 38 to position the shoe lengthwise in the machine.

75 After the shoe has been positioned in the ma-

chine the crease plates 42 are moved further into the rand crease of the shoe in order to serve as supports for the sole while it is being operated upon, first by a back cutter (not shown), which is constrained for movement in a variable U-shaped path controlled by the position of the crease plates 42 to trim material from and bevel the margin of the heel end of the sole, and then by a shoulder-forming cutter (not shown) which moves transversely across the sole in the vicinity of its breast line. The crease plates 42 when swung toward each other about the axis which passes through point 44 are moved into engagement with adjustable screws 58 respectively, which are carried by the swinging arms 50. The crease plates 42 are moved toward each other through suitable mechanism, which is described in detail in the above-mentioned United States Letters Patent and is controlled by a hand lever 60, until they exert a predetermined pressure against the arms 50, thereby accurately centralizing the shoe and clamping the same against lateral movement while the sole is being trimmed.

If an attempt were made to position shoes off the last in the above-described machine without properly supporting the counter portion of the shoe from the inside, the arms 50 acting under the pressure of the crease plates 42 would crush in the counter portion of the shoe with the result that the shoe would not be accurately centralized or clamped in the machine.

In order further to insure that the shoe is clamped against movement while being operated upon, the above-identified machine is constructed and arranged to force, through mechanism 110 which will soon be described, the overlusted counter portion of the shoe into engagement with the underside of the crease plates 42 while such plates are being moved toward each other. In the illustrated construction this clamping pressure is utilized to force the angular forms 20a, 20b into engagement with the counter portion of the inside of the shoe to support the same against distortion by the arms 50.

The shoe mounted upon the jack, which may 120 be said to include the jack post 22 and parts mounted thereon, is forced against the crease plates 42 and is also forced rearwardly of the machine through a cam 62 (Fig. 1) operated by the hand lever 60 and constructed and arranged 125 to engage a pair of rolls 64 carried by the jack post 22, as it is swung rearwardly about the pin 40. When the cam 62 is swung to a rearward position about the pin 40 it raises the jack and thereby forces the overlusted counter portion of the shoe against the crease plates 42 and also forces the shoe rearwardly against the back gage 38. When the cam 62 is swung to a forward position to permit the operator to swing the post 130 forwardly about the pin 40 to a loading position shown in dotted outline in Fig. 1, it is moved out 135 of engagement with the rolls 64. It will be noted that the jack post 22 and the arms 50 are operated through springs 66 and 68, respectively, in order that the pressure applied to these members by moving the hand lever 60 will not be 140 greater than a predetermined amount and in order to cause the jack post 22 and the arms 50 to operate yieldingly.

The relative strengths of the springs 66 and 68 145 are such that upon downward movement of the hand lever 60, pressure is exerted by the forms 20a, 20b against the inside of the counter portion of the shoe just prior to the time that the arms 50 are forced by the crease plates 42 against 150

80

150

the outside of the counter portion of the shoe. The hand lever 60 is moved downwardly until the pressures exerted against the inside and the outside counter portions of the shoe are approximately equal. During the downward movement of the hand lever 60 and until the shoe is finally clamped, the pressure exerted against the inside counter portion of the shoe by the forms 20a, 20b is slightly in excess of the pressure exerted against the outside of the counter portion by the arms 50. This difference of pressure, however, is not sufficient to distort the counter portion of the shoe and insures that the arms 50 will not crush in the counter portion of the shoe as it is positioned and clamped in the machine. By providing the above arrangement shoes of different sizes and styles which are off the last may be effectively positioned and clamped in the above machine.

20 The block 24 and the head 25 which comprises the forms 20a, 20b and a plunger 76 through which such forms are supported upon the block 24 will now be described in detail. The block 24 is provided with a circular recess or guideway 72 of suitable size to receive a stem of the plunger 76, one side of the stem being provided with a slot 78 shaped to receive a pin 80 carried by the block. The pin 80 permits relative movement of the block 24 and the plunger 76 and also limits the extent of such movement under pressure of a spring 82 which is positioned within the circular recess 72. The top portion of the block 24 is bifurcated for the reception of a lower flange portion 84 of the plunger 76, which portion prevents the plunger from turning with respect to the block 24. The plunger 76 is constructed and arranged to support the forms 20a, 20b which, when expanded against the counter portion of the shoe substantially fill up the entire heel end of the shoe. The forms 20a, 20b are pivotally mounted at their rear ends upon a pin 86 which is in threaded relation with the lower flange portion 84 of the plunger 76. The upper surface 88 of the lower flange portion 84 serves as a support for the forms 20a, 20b as the same are moved toward and away from each other about the pin 86 through mechanism which will be described later. The plunger 76 is also provided with an upper flange portion 90 having a circular shape and arranged for reception within opposed slots 92 of the forms 20a, 20b. The flange portion 90 assists the lower flange portion 84 in supporting the forms 20a, 20b and also insures that during the operation of the machine such forms cannot be accidentally lifted off the pin 86.

55 In order to expand the form 20 each of the arms 20a, 20b is provided with a depending portion 94 constructed and arranged to engage a corresponding beveled face or wedge portion 96 of the upper end of the block 24. The plunger 76 and the forms 20a, 20b, are normally held in a raised position relatively to the block by the spring 82, the arrangement being such that the forms 20a, 20b when in a raised position contact with the upper ends of the wedge portions 96, respectively. The forms 20a, 20b are normally held together to assume a closed position when the plunger 76 is raised with respect to the block 24, by a torsion spring 98, which is included in recesses 100 of the forms and has its central portion coiled about the pin 86 and its opposite ends inserted in recesses 99 formed in the respective forms.

70 As the jack post 22 is raised by the cam 62 to force the overlasted counter portion of the shoe

against the crease plates 42, the jack post and the block are raised to cause the wedge portion 96 to engage the respective depending portions 94, thereby expanding the form 20 against the inside counter portion of the shoe. When the sole has been trimmed the hand lever 60 is raised to swing the cam 62 forwardly out of contact with the roll 64 and to move the arms 50 away from the counter portion of the shoe. When the cam 62 has been moved out of contact with the rolls 64 the spring 82 which is stronger than the spring 32, depresses the block 24 relatively to the forms 20a, 20b and permits the torsion spring 98 to move the forms 20a, 20b toward each other. The jack post 22 is then swung to its loading position (Fig. 1) to remove the shoe from the machine. It will be noted that in operating upon shoes on the last the last pin block of the machine is slidingly supported for movement along an undercut guideway 102 of the jack post 22 in order to permit the last pin block to shift from side to side to accommodate right and left lasts, the last thimbles of which are not centralized with respect to the median plane of the heel-seat portion of the last. When operating upon shoes off the last, however, the block 24 may be initially centralized along the guideway 102 of the jack post 22, after which it is clamped in such position by turning screws 104 carried by the block and having their respective inner ends in engagement with a yieldable portion 106 (Fig. 4) of the block.

25 Forms of different sizes and shapes may be positioned upon the plunger 76 if desirable according to the sizes and styles of shoes being operated upon. The top faces 108 of the forms 20a, 20b should support as much as possible of the heel end of the shoe in order that such faces will cooperate effectively with the crease plates 42 in clamping the heel portion of the shoe against such plates.

30 The opposite sides of the counter portion of the inside of the shoe are positioned at substantially equal distances from a median plane 110 of the heel-seat portion of the sole and forms 120 which are symmetrical may be used to centralize the shoe without the use of arms 50. Although the opposite portions of the inside of the shoe are of slightly different shapes, it has been found that if the side faces 112 (Fig. 1) of the forms 125 20a, 20b are approximately of the mean shape of the opposite sides of the counter portions, the forms will operate effectively to support the shoe against distortion and to centralize the same. It has been found preferable, however, initially to 130 centralize a shoe in the illustrated machine by the use of arms 50 before the shoe is forced against the crease plates, thereby positioning the shoe with a minimum amount of effort.

35 Although the above-described form 20 has been illustrated with reference to the heel-seat-fitting machine described in United States Letters Patent No. 1,902,824 it will be clear that the form may be advantageously used in various other types of machines.

40 Having thus described my invention, what I claim as new and desire to secure by Letters Patent of the United States is:—

45 1. A machine for operating upon shoes having, in combination, an expansible support shaped for reception within the heel end of a shoe, a plate shaped and arranged to enter the rand crease of the shoe, and means to force the shoe against said plate, said support being constructed and arranged for expansion to force the same

- into firm engagement with the counter portion of the shoe as the shoe is forced against the plate by said means.
2. A machine for operating upon shoes having, in combination, an expansible support shaped for positioning within the heel end of a shoe, a plate constructed and arranged to enter the rand crease of the shoe, and means yieldingly to force the shoe against the plate, said support being constructed and arranged firmly to engage the counter portion of the shoe as the shoe is forced against the crease plate and to cooperate with the crease plates in clamping the shoe against movement in the machine.
3. In a machine for operating upon shoes, a jack post, a head mounted on the jack post and including a pair of movable forms constructed and arranged for reception within the heel portion of a shoe, and means to cause relative movement of the head and the jack post lengthwise of the post, said head and jack post having cooperating surfaces so formed and arranged that relative lengthwise movement of the post and the head forces the forms against the counter portion of the shoe.
4. In a machine for operating upon shoes, a jack post provided with a wedge portion, a head mounted upon the jack post and comprising a pair of forms which are mounted for pivotal movement and are shaped for reception with the heel portion of a shoe, and means to move the jack post toward the head thereby causing the wedge portion to force the forms against the counter portion of the shoe.
5. In a machine for operating upon shoes, a jack post, a head mounted upon the jack post and including a pair of pivotally mounted forms constructed and arranged for reception within the heel portion of a shoe, and means, operated by movement of the jack post toward the head, for forcing the forms yieldingly against the counter portion of the inside of the shoe.
6. A machine for operating upon shoes having, in combination, an expansible form shaped for reception within the heel end of a shoe, a pair of plates constructed and arranged to engage the rand crease of the shoe mounted upon said form, a jack post upon which the form is mounted, and means including the post to force the form against the plates and to cause the post to move toward the form and to expand the same thereby forcing the form into engagement with the counter portion of the inside of the shoe.
7. A machine for operating upon shoes having, in combination, an abutment, an expansible form shaped for reception within the heel end of a shoe, a jack post constructed and arranged to support the form, members outside of the shoe mounted to engage opposite sides respectively of the counter portion of the shoe to centralize the same upon the form, and means operated by a lever constructed and arranged substantially simultaneously to force the shoe upon the form against the abutment, to move the forms into engagement with the inside counter portion of the shoe, and to move the centralizing members against the outside of the counter portion of the shoe to centralize the same.
8. A machine for operating upon shoes having, in combination, crease plates, an expansible form shaped for reception within the heel end of a shoe, centralizing members constructed and arranged to engage the opposite sides of the counter portion of the outside of the shoe, means comprising the crease plates arranged to force the centralizing members into engagement with the opposite sides of the counter portion to clamp the shoe, and mechanism to force the shoe against the crease plates to cause the form to expand thereby pressing the same against the counter portion of the inside of the shoe to prevent excessive distortion of the counter portion by said centralizing members.
9. A machine for operating upon shoes having, in combination, a jack comprising an expansible form shaped for reception within the heel end of a shoe, a plate to engage the rand crease of the shoe upon the jack, members movable into contact with the opposite sides respectively of the outside counter portion of the shoe to position the same widthwise in the machine, and mechanism comprising a hand-operated lever constructed and arranged to force the shoe against said plate to expand the form against the counter portion of the inside of the shoe and also to clamp the positioning members against the opposite sides of the counter portion of the shoe.
10. A machine for operating upon shoes having, in combination, a jack comprising a wedge and an expansible form shaped for reception within the heel end of a shoe, plates to engage the rand crease of the shoe, arms movable into contact with opposite sides respectively of the outside counter portion of the shoe to position the same widthwise in the machine, and mechanism operable by means of a hand lever constructed and arranged to force the shoe against the crease plates to cause the wedge to force the expansible form into engagement with the counter portion of the shoe and also to clamp the positioning arms against the opposite sides of the counter portion of the shoe.
11. A machine for operating upon shoes having, in combination, a jack comprising an expansible form shaped for reception within the heel end of a shoe, plates to engage the rand crease of the shoe, members movable into contact with opposite sides respectively of the outside counter portion of the shoe to position the same widthwise in the machine, and lever-operated mechanism constructed and arranged to force the shoe against the plates and to move the forms into engagement with the opposite sides of the counter portion of the inside of the shoe and also to clamp the positioning members against the opposite sides of the outside counter portion of the shoe, said mechanism comprising spring connections positioned between the lever on one hand and the expansible form and the positioning members on the other hand respectively.
12. In a machine for operating upon shoes, a jack post provided with a wedge portion and a slideway, a plunger mounted for movement along the slideway, a spring normally to hold the plunger in a raised position upon the jack post, a pair of forms having the general shape of the heel end of the inside of a shoe carried by and mounted for movement relatively to the plunger, means normally to urge the forms toward each other, and mechanism to cause relative movement of the jack post and the plunger, said forms being constructed and arranged for engagement with the wedge portions upon relative movement of the post and the plunger to force the forms into engagement with the counter portion of the inside of the shoe.
13. In a machine for operating upon shoes, a jack post provided with a wedge portion and a slideway, a plunger mounted for movement along the slideway, a pair of forms having the general shape of the heel end of the inside of a shoe carried by and mounted for movement relatively to the plunger, means normally to urge the forms toward each other, and mechanism to cause relative movement of the jack post and the plunger, said forms being constructed and arranged for engagement with the wedge portions upon relative movement of the post and the plunger to force the forms into engagement with the counter portion of the inside of the shoe.

- the slideway, a spring normally to hold the plunger in a raised position upon the jack post, a pair of forms having the general shape of the heel end of the inside of a shoe carried by and mounted for movement relatively to the plunger, means normally to urge the forms toward each other, a pair of plates shaped and arranged to enter the rand crease of the shoe, and means to force the jack post upon which the shoe is mounted toward the crease plates, said forms being constructed and arranged for engagement with said wedge portions as the jack post is moved toward the crease plates to force the forms into engagement with the counter portion of the inside of the shoe.
14. In a machine for operating upon shoes, a jack post provided with a guideway and having wedge portions, a member comprising a bearing face and a stem shaped to fit within the guideway, forms supported upon said face and mounted for pivotal movement, said forms being constructed and arranged to be forced against the counter portion of the inside of a shoe mounted upon the forms by the wedge portions respectively upon movement of the post toward said forms, means to move the jack post relatively to the forms, resilient means to move the forms out of wedging relation with said wedge portions, and means carried by the forms normally to urge the same together.
15. In a machine for operating upon shoes, a jack post, a pair of forms mounted upon the jack post and relatively movable to engage the counter portions of the insides of shoes of various sizes, a member upon which the forms are mounted for movement and comprising a portion shaped for reception by the post, a spring to support the member upon the post, and means to cause relative movement of the member and the post, said post having wedge surfaces constructed and arranged to engage the forms to cause the same to move relatively to each other upon relative movement of the member and the post.
16. A machine for operating upon shoes having, in combination, a jack post provided with a guideway, a pair of pivotally movable forms, a member comprising a bearing portion constructed and arranged to support the forms and having a stem portion shaped for reception within the guideway, a spring arranged normally to retain the forms in a raised position upon the post, means to move the post toward the forms, said post having faces constructed and arranged to engage the forms respectively to force the same into engagement with the counter portion of the inside of a shoe mounted upon the forms upon movement of the post toward the forms, and a spring carried by the forms normally to move the same toward each other.
17. A machine for operating upon shoes having, in combination, a jack post provided with a guideway, a pair of pivotally movable forms shaped for reception within the heel end of a shoe, a member comprising a bearing portion constructed and arranged to support the forms and shaped for reception within the guideway, a spring tending normally to retain the forms in a raised position upon the post, crease plates constructed and arranged to engage within the rand crease of the shoe, said jack post having faces constructed and arranged to engage the forms respectively, and means to force the jack post toward the crease plates to cause the forms to be forced against the counter portion of the inside of the shoe and to cooperate with the crease plates in clamping the shoe in the machine.
18. A machine for operating upon shoes having, in combination, a jack post provided with wedge portions, a member yieldingly supported by the post, a pair of forms carried by the member and mounted for movement to engage the counter portions of the insides of shoes of varying sizes, said forms comprising depending portions shaped and arranged for engagement with the wedge portions to cause the forms upon movement of the post relatively to the forms to be forced against the counter portion of a shoe mounted upon the forms, and means to move the post relatively to the forms.
19. A machine for operating upon shoes having, in combination, a jack post provided with wedge portions, a member yieldingly supported by the post, a pair of forms provided with angularly disposed faces carried by the member and mounted for pivotal movement to engage the counter portions of the insides of shoes of varying sizes, crease plates to engage the overlasted counter portions of a shoe mounted upon the forms, said forms comprising portions shaped and arranged for engagement with said wedge portions to cause the forms upon movement of the post relatively to the same to be forced against the heel seat and the counter portions of the inside of the shoe, and means to move the post relatively to the crease plates.
20. A machine for operating upon shoes having, in combination, relatively movable forms shaped for reception within the heel end of a shoe, means to engage the overlasted counter portion of the upper of the shoe, and mechanism to force the shoe against said means, said forms being constructed and arranged to be forced into engagement with the inside counter portion of the shoe thereby centralizing the same as the shoe is forced against said means by said mechanism.

EARL A. BESSOM.
